UNITED STATES PATENT OFFICE.

LEMAN E. DOTY AND GEORGE LAMBERTON, OF ELYRIA, OHIO.

CARBON-CAP-OPERATING MECHANISM.

Application filed August 6, 1921. Serial No. 490,263.

To all whom it may concern:

Be it known that we, LEMAN E. DOTY and GEORGE LAMBERTON, citizens of the United States, and residents of Elyria, in the county of Lorain and State of Ohio, have invented certain new and useful Improvements in Carbon - Cap - Operating Mechanisms, of which the following is a specification.

This invention relates to by-product coke plants and more particularly to reversing mechanism for such plants, and has for one of its objects the provision of mechanism that will be entirely automatic in operation.

Another object is to provide improved mechanism of this class for the carbon caps of the ovens that will be so interlocked with the gas cock and other reversing mechanism of the plants that it will at all times operate in its proper order.

By-product coke plants are heated by gas, which flows through mains on each side of a battery of ovens, which sides are known as "coke side" and "pusher side", respectively. The gas flows upwardly through suitable risers from the mains to each oven. The gas from the main on the coke side is burned for a period of time, then cut off the coke side and burned from the main on the pusher side for a period, thus heating the ovens in the same manner as in ordinary reversible, regenerative heating units. The reversals of the gas, air, and stack dampers of the ovens have heretofore been made automatically by means of a clock to which is connected timing mechanism, which actuates controls of motors operating machines for making these reversals.

The connection between the gas riser and oven is made by a gas gun, having openings for the entrance and exit of gas, and also an opening to outside air, for the purpose of admitting air into the gas flues in the ovens when the gas is on at the other side of the battery. This opening is covered by a tight fitting cap commonly called the carbon cap. The carbon caps on the individual ovens are connected so that all the carbon caps on each side of a battery are seated or raised together. These carbon caps have heretofore been manually operated. The carbon caps on either side must be closed before gas is admitted to the gas guns on that side, since if they are not gas will escape into the air, become ignited, and cause serious fires and explosions. To overcome this danger, the manually operated carbon caps

have been electrically interlocked with the gas reversing mechanism, so that gas could not be turned on when the carbon caps were not seated. However, when the time arrived for a reversal of the gas, if the operator had not closed the carbon caps on the proper side, the reversing operation would not be completed, which resulted in irregular heating of the ovens, and in damage of the ovens, and deterioration in the quality of coke produced. The interlock with the gas valve, however, does not prevent the operator opening the carbon caps before all of the gas has left the mains, and, as has often happened, if the operator opens the carbon caps too soon after cutting off the gas from that side of the ovens, enough gas remains in the gas gun and oven flue to cause explosions which damage the oven brick, seals, and the gas gun.

The present invention provides for an automatic mechanism for operating the carbon caps, which mechanism is so interlocked with the other reversing mechanisms, that it must be performed in the proper order and at the proper time, thus eliminating all difficulties of the prior constructions.

In the drawings, Figure 1 is a somewhat diagrammatic side elevation of the pusher and coke sides of a battery of coke ovens.

Figures 2, 2^A and 2^B are diagrams of the circuits necessary to automatically operate the several reversing mechanisms, all three of these figures being interfitting so that complete circuits may be followed.

Referring particularly to the diagrammatic showing of Figure 1, the numerals 2 and 3 designate the gas mains for the pusher and coke sides of a battery, respectively, which are connected to the respective ovens by risers 4 and 5, respectively.

Each of the risers connects with an oven gas gun 6, one of which is provided for each oven and serves to distribute the gas in the oven flues. Gas valves 7 are mounted in each of the risers 4 and 5, and all other valves 7 on each of the respective sides of the battery are connected together by cables 8 and 8^A, and operated by gas cock machines 9 and 10 for the pusher and coke sides, respectively.

Each of the gas guns 6 is provided with an air inlet port closed by a tightly fitting carbon cap 11, and the caps 11 on each of the respective sides of the battery are connected together by cables 12 and 12^A, and

operated by carbon cap machines 13 and 14 for the pusher and coke sides respectively.

The gas mains 2 and 3 are supplied with gas from a gas tank 15 through a main 16.

5 A stack flue 17 extends along both sides of the ovens and is provided with air stand pipes 18 having covers or valves 19 adapted to be opened on the burning side of the ovens and closed on the opposite side. Dampers 10 20 are mounted in the flue 17 and are adapted to be lowered to closed position to shut off the flue from the stack on the side of the ovens being fired, and raised to open the flue to the stack on the opposite side. It is 15 essential that the valves 19 and stack flue dampers be operated simultaneously; therefore they all are operated by the one reversing machine 21, the valves 19 and 20 on the pusher side of the ovens being connected 20 by one cable 22 to the machine 21, and the valves 19 and damper 20 on the coke side of the ovens being connected by a cable 23 to the machine 21. The cables 22 and 23 are wrapped around a single drum in the machine 21, and therefore the operation of the valves 19 and dampers 20 on the pusher and coke sides is simultaneous.

30 The several reversing machines are of common and well known construction, and therefore will not be gone into in detail, since their construction does not form a part of this invention. It will be noted, however, that each of the reversing machines 9, 10, 13, 14, and 21 are electrically driven by 35 motors built into and forming an integral part of the machines.

40 A time clock 25 is provided for each battery of ovens and is adapted to make a circuit to the timing device 26, having a timing drum which is provided with a plurality of contacts *a*, *b*, *c*, *d*, *e*, and *f*, which is electrically driven by a motor 40 forming a part of the timing device.

45 The time clock 25 is provided with a plurality of cams 32, 33, 34, and 35 adapted to actuate contactors 36, 37, 38 and 39, respectively, to make and break circuits to be hereinafter described.

50 The mechanical operation of the parts thus far described are as follows: Assuming that the gas is burning on the pusher side of a battery, the parts on the pusher side would be in the following positions, the carbon caps 11 would be closed, the gas cocks 55 or valves 7 would be open, the air valves 19 would be open, and the stack damper 20 would be closed. The position of the parts on the coke side of the battery would be the reverse from the pusher side. That is, 60 the carbon caps 11 would be open, the gas cocks or valves 7 would be closed, and the stack damper 20 would be open.

When reversing the following order is followed: First the carbon caps 11 on the coke side are closed; second, the gas cocks or

valves 7 on the pusher side are closed; third, the air valves 19 on the pusher side are closed, and the damper 20 on the pusher side is opened. Also the air valves 19 on the coke side are opened and the damper 20 on the coke side is closed; fourth, the gas cocks or valves 7 on the coke side are opened; and fifth, after an interval of three to five minutes, the carbon caps 11 on the pusher side are opened. All of the above operations are automatic and must follow in the prescribed order or the complete reversal will stop, due to the novel interlock features which will be clearly brought out in the description of the wiring diagram which follows:

75 Referring to the wiring diagram of Figures 2, 2^A and 2^B, the position of the timing and starting apparatus is such that a reversal is about to be started, and assuming 80 that the gas is on the pusher side and about to be reversed to the coke side, as described above.

85 The timing clock 25 will move the cam 33 far enough to allow contactor 37 to close, which will close a master timing circuit from the plus side of switch 42, through wire 43, cable 44, wire 45, contacts 46, wire 47, contact 48, wire 49, contact 50, wire 51, cable 44, wire 52, to contactor 37, through contactor 37, wire 53, contacts 54, and 55, on the timing drum of the timing device to wire 56, through one-half of a double magnet coil of a double coil, contactor 57 to wire 58, to the minus side of switch 42, thus closing the contactor 57. Closing of contactor 57 closes the armature circuit of the timing motor 40, thus setting the timing device 26 in motion to open and close contacts *a* to *f* inclusive of the timing drum. The circuit 100 for the timing motor is as follows: From the plus side of switch 42 through wire 59, to one side of the armature of motor 40, through the armature to wire 60, through the contactor 57 to wire 58 to the minus side 105 of the switch 42.

110 As shown, the contact *a* on the timing drum would be the first to close and the subsequent operation will be now traced for one cycle or one reversal of gas.

115 Closing of the contact or switch *a* completes a circuit from wire 52 through the contact *a* to wire 61, cable 62, wire 63, cable 64, wire 65 to the limit switch 66 (Fig. 2^B) for carbon cap machine 14. The circuit is 120 now through the two top contacts 67, and 68 of this switch, through wire 69 to the magnet coil of magnetic switch 76 on the controller for carbon cap machine motor 70^a, through the magnet coil to wire 71 to the minus side of the line. The above circuit will cause switch 70 to close and make a circuit to the armature 72 of the motor 70^a of carbon cap machine 14 as follows: From plus side of line through wire 73, 125

switch 76, wire 74, armature 72, wire 75 to minus side of line, thus causing the carbon cap machine motor to operate to close the carbon caps 11 on the coke side of the battery.

The motor 70^a of carbon cap machine 14 will continue to operate until the limit switch 66 has moved from the position indicated by dotted lines 1—1 to position 2—2, or in other words until the contacts on the line 2—2 are under the fingers of the limit switch instead of the contacts on the line 1—1. When the switch 66 has reached this new position the circuit from wire 52 to the magnetic coil of switch 70 will be broken through wire 69, de-energizing the coil of switch 70, and allowing said switch to open, thus breaking the circuit to the armature 72 of the motor of carbon cap machine 14.

It will, of course, be understood that the switch 66 is so positioned and adjusted that when the motor of carbon cap machine stops, the carbon caps 11 will be closed.

As soon as the carbon cap limit switch 66 has moved from the position indicated by the dotted lines 1—1 to the position 2—2, a circuit will be established from wire 65 through the third pair of contacts 80 and 81, from the top of switch 66 through wire 82 to the top pair of contacts 83 and 84 on the gas cock limit switch 85, through wire 86, cable 87, wire 88 to magnet coil of magnetic contactor 89 of the controller for motor 90 of gas cock machine 9, then through the coil of contactor 89 to wire 91, to area of resistance starter 96 and to wire 97, to the minus side of line. The energizing of contactor 89 will cause said contactor to close, completing a circuit to the armature of gas cock motor 90, of gas cock machine 9, from plus side of line through wire 92, through contactor 89, and wire 93, to one side of the armature 94 of motor 90, then through the armature 94 to wire 95 through a resistance type starter 96 and wire 97 to minus side of line.

The above circuit being complete, gas cock motor 90 will operate until limit switch 85 moves from position indicated by dotted lines 1—1 to position 2—2, at which time gas cock motor 90 will stop, due to breaking of the circuit to the magnetic contactor 89, which de-energizes said contactor causing it to break the circuit to the motor armature. Switch 85, however, is so adjusted and positioned that all the gas cocks operated by the machine 9 will have been closed when the motor stops.

During the operations, the timing drum 60 of the timing mechanism has been continuously revolving and has reached a point where contact or switch *b* is about to close. Closing of the contact *b*, will make a circuit from wire 52 through contact *b*, to wire 98, cable 82, wire 99, cable 64, wire 100 to

contacts 101 and 102 of gas cock limit switch 85, this switch having moved from position indicated by dotted line 1—1 to position 2—2. From contact 102 the circuit is through wire 103 to a top contact 104 of limit switch 105 of reversing machine. From contact 104 the circuit is to contact 106, to wire 107, cable 87, wire 108, contactor 109 on controller for motor 110 of reversing machine 21, through coil of contactor 109 to wire 112, through arm of resistance type starter 113 to wire 114 to minus side of line.

The above circuit will cause the energization of the coil of contactor 109, thus closing the contactor and making a circuit to the reversing machine motor 110 as follows: From plus side of line through wire 115, through contactor 109 to wire 116 to one side of the motor armature, through the armature to wire 117 to the resistance of resistance type starter 113 to the arm of said starter, through the said arm to wire 114 to minus side of line.

Reversing motor 110 will continue to operate until its limit switch 105 has moved from the position indicated by dotted lines 1—1 to position 2—2 when the control circuit to the contactor 109 will be broken, de-energizing the coil of said contactor and allowing it to open. When the contactor 109 opens it will break the circuit from the plus side of the line to the motor 110 and, therefore, the motor will stop. The switch 105 is so arranged and adjusted that the position of the air valves 19 and stack dampers 20 will be reversed when the circuit is broken to motor 110.

As the timing drum continues to rotate, the switch or contact *C* will close, making a circuit from the wire 52 through the switch *C*, to wire 120, to cable 62 to wire 121, to cable 64, to wire 122, to third pair of contacts 123 and 124, from top of limit switch 105, then through wire 125 to fourth pair of contacts 126 and 127 on limit switch 66. From the contacts 126 and 127 of limit switch 66, the circuit is through wire 128 to the two top contacts 129, 130, of limit switch 131 for gas cock machine 10; from contact 130, the circuit is through wire 132, cable 87, wire 133, to coil of contactor 134 on controller for the motor 135 of gas cock machine 10, thence through the coil of contactor 134 to wire 136, to the arm of a resistance type starter 137, to wire 138, and to minus side of line.

The above circuit will energize the contactor 134 causing it to close and complete a circuit to the motor 135 as follows: From the plus side of line through wire 139, through contactor 134, to wire 140, to one side of the armature of motor 135, through the armature to wire 141, to the resistance of resistance type starter 137, to the arm of

said starter and through wire 138 to minus side of line.

The motor 135 of gas cock machine 10 will continue to operate until the limit switch 131 has moved from the position indicated by dotted lines 1-1 to position 2-2, thus breaking the circuit to, and de-energizing contactor 134, which will open, breaking the circuit to the motor.

10 The reversal is now complete, with the exception of the operation of the carbon cap machine 13, which must still operate to open the carbon caps 11 on the pusher side of the battery.

15 When the gas cock limit switch 131 has moved from position indicated by dotted lines 1-1 to position 2-2 a circuit path is completed to the controller for carbon cap motor 145, with the exception of the contacts or switch 38 operated by cam 35 as follows: From contact or switch 38 to wire 146, to third pair of contacts 147 and 148, from top of limit switch 131, to wire 149 to contacts 150 and 151 of limit switch 152 on controller for carbon cap motor 145, through the coil of contactor 154 to wire 155, to minus side of line.

The above circuit remains broken at the switch 38 until the cam 35 is moved sufficiently by the clock 25 to allow said switch to close, which cam will operate about three minutes or longer if desired, after the other reversals have all been made, thus giving time for all gas to leave the mains on that side. As soon as switch 38 closes, the circuit is completed from the plus side of line through the switch 38 and above described path, and the coil of magnetic contactor 154 is energized, thus closing contactor 154 and completing a circuit to motor 145 from plus side of line as follows: From plus side of line through wire 158 to contactor 154, through contactor 154 to wire 159, to one side of the armature of motor 145, through the armature of motor 145 to wire 160 to minus side of line.

40 The motor 145 will continue to run until carbon cap limit switch 152 has moved from the position indicated by dotted lines 1-1 to position 2-2 at which time the circuit will be broken to the coil of magnetic contactor 154, thus de-energizing said coil and causing the contactor to open and break the circuit to the motor 145.

45 During the above operations, the timing drum of the timing device continues to revolve until the sliding contact 54 passes beyond its finger, thereby breaking the circuit to the coil of contactor 57. However, when the circuit is broken by the movement of contactor 54, it is again made in the reverse direction by sliding contact 161 through wire 162 to switch 36 adapted to be actuated by cam 32 when the next reversal is started.

55 The time clock 25 will actuate the cams 32

and 34 about thirty minutes after the carbon cap machine 13 has stopped operating. Exactly the same operation as described above will take place only in the reverse order, that is, the cam 32 will actuate switch 36 to make 70 a circuit to the timing motor 40 and said motor will drive the timing mechanism so as to close the switches or contacts *d*, *e*, and *f*, of the timing drum to make the several circuits above described to the several reversing motors, as will be readily apparent to those skilled in the art. It will, of course, be understood, as explained above, that the circuit to the cam operated switches of the clock 25 through contacts 54 and 55 is broken 80 and a new circuit established through contacts 55, 161 and wire 162 to the cam operated switches.

The reverse order of operation will be first to make the circuit to carbon cap motor, then 85 to gas cock motor, then to reversing machine motor 110, then to gas cock motor 90, and lastly to carbon cap motor 70^a.

The above detailed description of one apparatus and one complete cycle of operation 90 of the improved apparatus is described as it actually takes place in practice, and it will be understood that we do not wish to be limited thereto, since various modifications may be made in the apparatus and the operations 95 without departing from the spirit of our invention as defined in the appended claims.

We claim:—

1. The combination with a battery of by-product coke ovens having the usual fuel 100 gas cocks, air valves and carbon caps, of separate electrically operated means for opening and closing said fuel gas cocks, air valves and carbon caps, means for automatically making the circuits to said first named 105 means, said last named means including a timing mechanism and circuit interlocking elements, said timing mechanism being so arranged that said fuel gas cocks, air valves and carbon caps will operate at separate 110 times in a certain prescribed order, and said interlocking elements being adapted to prevent the making of the circuits to any of said first named means upon the failure of the circuit to the preceding one of said means 115 in order.

2. The combination with a battery of by-product coke ovens having the usual fuel gas cocks, air valves, carbon caps, of electrically operated separate gas cocks, carbon caps and reversing machines for opening and closing the gas cock, carbon cap and air valves, respectively, means for automatically making the circuits to said machines, said means including a timing mechanism and circuit interlocking elements, said timing mechanism being arranged and operated to cause the circuits to said cock, carbon cap and reversing machines to be made at separate times in 125 a prescribed order, and said interlocking ele- 130

ments being adapted to prevent the making of the circuit to said machines upon the failure of the circuit to the preceding machine in order.

3. The combination with a battery of by-product coke ovens having the usual fuel gas cocks, carbon caps, reversing dampers, and air valves arranged on both the pusher and coke sides thereof, of electrically operated 10 gas cock and carbon cap machines for opening and closing said gas cocks and carbon caps, respectively, and an electrically operated reversing machine for opening and closing said air valves and said dampers, means 15 for automatically making the circuits to

said machines, said means including a timing mechanism and circuit interlocking elements, said timing mechanism being arranged and operated to cause the circuits to said gas cock, carbon cap and reversing machines to be made at separate times in a prescribed order, and said interlocking elements being adapted to prevent the making of the circuits to said machines upon the failure of the circuit to the preceding machine in 20 order.

In testimony whereof, we have hereunto set our hands.

LEMAN E. DOTY.
GEORGE LAMBERTON.
